ENGINE STARTER CONTROL APPARATUS

John B. Dyer, Dayton, Ohio, assignor to General
Motors Corporation, Detroit, Mich., a corpora-
tion of Delaware

Application July 12, 1934, Serial No. 734,739
Renewed November 8, 1939

21 Claims. (CL. 290—38)

This invention relates to a system of control for the starting apparatus of internal combustion engines and particularly to those engines used on automotive vehicles.

This application is a continuation in part of the copending application of John B. Dyer, Serial No. 653,983, filed January 28, 1933, for Engine control system. That application discloses a circuit which requires the closing of the ignition switch and the closing of a switch coordinated with the engine throttle actuator in order to establish a relay magnet circuit whereby a starter control relay switch is closed in order to effect the completion of a circuit to an electromagnetic device which causes an electric starting motor to be mechanically connected to the engine and to be electrically connected with a current source in order to crank the engine.

The present application describes and claims the electromagnetic gear-shifting and motor-switch closing device, claims to which were originally presented in Dyer's application, Serial No. 653,983, and were divided out; and the present application also discloses an assembly unit in which the said electromagnetic device originally disclosed in Dyer's application, Serial No. 653,983, is combined structurally with the starter control relay switch.

Accordingly, the objects of the invention of the present application reside in certain improvements in electromagnetic devices whereby the efficiency of their operation, the durability of their construction and the economy of their manufacture are realized.

Further objects and advantages of the present invention will be apparent from the following description, reference being had to the accompanying drawings wherein a preferred embodiment of the present invention is clearly shown.

In the drawings:

Figure 1 is a wiring diagram illustrating the use of the present invention;

Figures 2 and 3 together show a fragmentary view of the engine starting apparatus equipped with the electromagnetic device constituting a part of the present invention, said device being shown in longitudinal cross section;

Figure 4 is a sectional view on line 4—4 of Figure 2;

Figure 5 is a perspective view showing the electromagnetic device of Figure 2 combined structurally with the starter switch relay 80 of Figure 1;

Figures 6 and 7 show in perspective certain disassembled parts of the unit shown in Figure 5;

Figure 8 is a fragmentary sectional view on the line 8—8 of Figure 5; and

Figure 9 is a fragmentary view looking in the direction of arrow 9 of Figure 5 showing the starter switch relay, the bracket of which is broken away.

In Figure 1, 20 designates a generator grounded at 21 and connected by a wire 22 with the current winding 23 of a reverse current relay 24. Winding 23 is connected with the frame 25 of relay 24 which frame supports a leaf spring hinge 26 to which one end of the armature 27 is attached. Armature 27 carries a contact 28 engageable with its stationary contact 29 carried by bracket 30 connected by wire 31 with an ammeter 32 connected by wires 33 and 34 with the battery 35 grounded at 36. This completes the generator to battery circuit. A voltage coil 37 is connected with the relay frame 25 and is grounded at 38.

20 The frame 25 supports a core 39 which is surrounded by the windings 23 and 37 although these windings are shown in the drawings as separated from the core 39. The relay contacts 28 and 29 are closed to complete the battery charging circuit due to the magnetic action produced by current flowing through the voltage winding 37 after the generator has attained a certain voltage. When the contacts 28 and 29 are closed, current then flows through the winding 23 which then cooperates with winding 37 to hold the armature 27 in position to maintain the contact 28 in engagement with the contact 29. It is therefore apparent that the relay can be adjusted so that its contacts will not be separated due to the action of the spring hinge 26 until after the voltage of the generator has fallen substantially below that voltage required for the closing of the relay contacts 28 and 29.

The main engine cranking circuit comprises

40 the battery 35, wire 34, switch contact 40, movable contact 41, switch contact 42, wire 43, starting motor 44 which is grounded at 45, and battery ground connection 36. The starting motor 44 operates the shaft 46 along which slides a sleeve 47 which is splinedly connected to the shaft 46 and which is operatively connected through a one-way or overrunning clutch 48 with a pinion 49 engageable with the engine flywheel gear 50. The sleeve 47 is surrounded by

45 a grooved collar 51 which is slidable along the sleeve 47 but normally is held against a shoulder 52 at the left end of the sleeve 47 by a spring 53 interposed between the collar 51 and the clutch 48. The collar 51 is caused to move toward the

50 right in the drawings by lever 54 pivotally mounted

ed upon a shaft 55 and carrying at its lower end a pin 56 received by the groove of the collar 51. Movement of the lever 54 counterclockwise will cause the sleeve 47 to be moved toward the right and the pinion 49 to become engaged with the fly-wheel gear 50. The pinion 49 is withdrawn from the gear 50 by the operation of a spring 57 which surrounds the shaft 55 and bears at one end against a stationary stop 58 and at the other against a stop 59 carried by the lever 54.

The lever 54, shown in Figs. 2 and 3 is actuated and the switch 40, 41, 42 is closed by electro-magnetic means which comprises a solenoid core 60 and a solenoid armature 61 which are surrounded by electromagnet windings 62 and 63. The solenoid core 60 is provided with a central bore for receiving a horizontally slideable plunger or rod 64 provided with two shoulders 166 and 179 between which an insulatingly mounted movable contact 41 is relatively slideable. A spring 174 urges the contact 41 against the shoulder 166. The rod 64 is normally held in the position shown in the drawings with its shoulder 179 bearing against the magnet core 60 due to the action of a spring 164 bearing at one end against the shoulder 166 and at the other end against a stationary part 156 having a projection 162 tele-scopically fitting within a recess or central bore 161 in the rod 64. The solenoid armature 61 is connected by a pin 74 with a link 75 which carries a stud 76 received by a slot 77 provided in the upper end of the lever 54.

When sufficient current passes through the windings 62 and 63, the armature 61 is caused to move toward the left in order to effect counter-clockwise movement of the lever 54 and the movement of the pinion 49 into mesh with the engine gear 50. This movement of the solenoid 61 also causes the rod 64 to move to the left carrying with it, due to the action of the spring 174, the switch contact 41 which is yieldingly pressed into engagement with the contacts 40 and 42 due to the yielding action of the spring 174. When this occurs, current will flow from the battery to the motor 44 thereby causing rotation of its armature shaft 46 and the pinion 49 driven thereby through the splinedly connected sleeve 47 and the overrunning clutch 48, thereby causing the fly-wheel gear 50 to rotate and the engine to be cranked for starting purposes. Should the engine fail to start and the pinion 49 fail to be withdrawn from the fly-wheel gear 50 by the action of the spring 57, it is possible to open the circuit of the starting motor by disconnecting the magnet coil windings 62 and 63 from the storage battery, the connections to which are to be described later. When the magnet coils 62 and 63 are deenergized, movement of the contact 41 away from the contacts 40 and 42 by the action of spring 164 may take place due to the fact that the solenoid 61 may move toward the right slightly although the lever 54 may not be turned. This is possible due to the lost-motion connection provided by the pin 76 and the slot 77 between the solenoid armature 61 and the lever 54.

Should the end faces of the teeth of the pinion 49 abut with the end faces of the gear 50 before meshing, it is possible to close the motor circuit in order that the pinion 49 may be rotated into meshing relation with the engine gear 50. This is possible due to the fact that the motor switch 40, 41, 42 can be closed before the meshing of pinion 49 with gear 50 takes place. The sole-

noid armature 61 operates to close the motor switch and to move the pinion 49 toward the gear 50, but after the pinion 49 collides with the gear 50, the spring 53 is compressed beyond its initial state of compression. Then when the motor shaft 46 turns to relieve the condition of gear tooth abutment, the spring 53 is released quickly to snap or jump the pinion 49 into engagement with the engine gear 50.

10 The circuit for connecting the magnet windings 62 and 63 with the storage battery 35 comprises the following circuit: Battery 35, wire 34, contact 40, frame 81 of the starter control relay 80, leaf spring hinge 82, armature 83, contact 15 84, stationary contact 85, bracket 86, wire 87, winding 63, ground connection 88 and battery ground connection 36. Stop 83a limits upward movement of armature 83. The circuit of the other winding 62 includes the foregoing circuit 20 as far as the bracket 86. From the bracket 86 a wire 90 leads out to connect with the coil 62 which is connected by wire 90a with the contact 42. The circuit of coil 62 is completed to the battery through the motor 44 and ground connections 45 and 36. It is apparent that when the contacts 84 and 85 of the starter relay 80 are closed, current will flow through both windings 62 and 63 to cause the solenoid 61 to move toward the left in order to shift the pinion 49 into engagement with the gear 50 and to close the motor switch 40, 41, 42. When the motor switch closes, the winding 62 will be short circuited. The winding 62 is made preferably of relatively coarse wire whereas the winding 63 is constructed of relatively fine wire. Both windings 62 and 63 are required to draw the armature 61 across to the core 60 but, when this relation has been established, the one winding 63 is all that is required to maintain this relationship. 30 Therefore the winding 62, which consumes the greater amount of the current, is short circuited so that the starting motor will have adequate current for cranking the engine.

35 The circuit of the engine starter control relay 45 80 comprises battery 35, wire 34, wire 33, ammeter 32, wire 91, stationary contact 92 of ignition switch 93, movable contact 94, stationary contact 95, wire 96, switch 97, wire 98, relay magnet coil 99 surrounding core 100, wire 101, bracket 102, contact 103 cooperating with movable contact 104 insulatingly carried by armature 27 of cut-out relay 24, wire 105, and ground returns 38, 36 to battery 35. When the movable switch contact 94 of ignition switch 93 engages contacts 92 and 95 it also engages a contact 106 connected by a wire 107 with the ignition apparatus of the engine. The switch 97 is one which is closed manually and is opened automatically when the engine starts. The switch 97 is preferably actuated by the engine throttle actuator or accelerator pedal. It is opened automatically preferably by means responsive to engine intake suction. The switch contacts 103, 104 of the cut-out relay 24 are normally closed.

60 65 To start the engine, the operator turns on the ignition switch 93 to cause the contact 94 to engage contact 92, 95 and 106. The operator closes the switch 97 preferably by means coordinated with the accelerator. This causes current to flow from the battery through the coil 99 of the starter control relay 80 whereupon contacts 84 and 85 are closed, whereupon the magnet coils 62 and 63 are energized to effect the shifting of the starter pinion 49 into mesh with the

engine fly-wheel gear and then closing of the main motor switch 40, 41, 42. The engine therefore starts in the manner described. When the engine becomes self-operative, suction produced by the engine will open the switch 97, and in response to the voltage of the generator 20 driven by the engine, the switch 103, 104 will be open. Hence the circuit of the coil 99 of the starter control relay 80 is opened by two switches connected in series to insure the discontinuance of the engine starting function as soon as possible after the engine becomes self-operative and the prevention of the operation of the starter thereafter or until the engine has stopped.

The construction of the magnet may be varied within certain limits, but it is desirable that the coil 63 shall contain a smaller number of turns than the coil 62, and the resistance of the coil 63 should be higher than the coil 62 so that the flow of current through the coil 63 is as low as possible to insure that the armature of the magnet be held in switch closing position during the cranking operation, so as to change that position as little as possible. It has been found desirable to provide coils having such resistances that for a six volt battery system, the flow of current through coil 63 is substantially from 8 to 10 amperes and through the coil 62 from 40 to 50 amperes before the starter switch is closed. The flow of current through the coil 62 is very brief, as it takes an almost imperceptible time to effect closing of the starting motor switch so that during most of the starting operation there is only from 8 to 10 amperes flowing through the coil 63 to hold the starting motor switch closed and the pinion in gear-engaging position.

It has been found that in order to cause proper opening of the main starter switch 40, 41, 42 upon opening of the ignition switch or the switch 97, the number of turns in the inner, or "pull in" coil 62 of the starter magnet must be somewhat greater than the number of turns in the outer, or "hold in" coil 63. This is true because when either switch above referred to, is opened while the starter switch is closed, current will flow from the battery through the starter and thence through the coils of the starter magnet to ground, the direction of current in the inner coil being the reverse of that in the outer coil.

As a concrete example of the operation it may be assumed that the switch 97 is opened by suction and the starter switch should open immediately. On opening of switch 97, however, current will flow from the battery to ground through connection 36 and from the battery through wire 34, the starter switch 40, 41, 42, wire 91 through the coil 62, thence through wire 90, wire 87, the coil 63 to ground 88, the direction of flow through coil 62 being reversed while the direction of flow through coil 63 remains the same. At this time the coils tend to neutralize each other and in order to insure that the magnetic flux passes through the zero point immediately, a slightly larger number of turns are used in the inner coil 62. The outer coil 63 may comprise 122 turns of #16 B. E. copper wire, and the inner coil 127 turns of #11½ B. E. copper wire. With this arrangement, as the flux passes through the zero point upon reversal of polarity of the inner coil 62 on opening of the suction operated switch 97, the magnet becomes completely deenergized and the starter switch is opened by the spring 164, as the spring 57 retracts the armature 61 and demeshes the pinion 49.

Theoretically, it might be possible to effect opening of the starter switch 40, 41, 42, with coils having the same number of turns, but owing to the residual magnetism of the magnet, inequalities in the wire resulting in varying resistances, and manufacturing inaccuracies, it is impossible to use coils of the same number of turns as the magnetic flux might not reach zero value. To make sure that the flux pressure does always pass through the zero point, it is necessary to provide at least a few more turns in the inner coil than the outer.

The particular system shown in Figure 1 constitutes an improvement in the system disclosed in Dyer's application #653,983, and is described and claimed in the copending application of John B. Dyer and William Earl Brown, Serial No. 735,102, filed Jan. 9, 1934 which became Patent No. 2,105,723 on January 18, 1938.

Forms of accelerator-closed engine-suction opened switch 97 are described and claimed in the copending application of John B. Dyer, Serial No. 734,740, filed July 12, 1934, which became Patent No. 2,167,646 on August 1, 1939.

In Figures 2, 3 and 4, the specific construction of the starter magnet is fully illustrated. This magnet comprises an outer shell 120 enclosing an inner shell 122 which in turn encloses a spool comprising a brass tube or sleeve 124 surrounded by an insulating tube 125, insulating washers 126 and steel washers 128, said tube and washers being held in place between an annular rib 129 and an annular flange 130 provided by the tube or the sleeve 124. Upon this spool are wound the coils 62 and 63. The shell assembly comprising the members 120 and 122 is closed at the right hand end by a cover assembly comprising a washer 132 and a washer 134 having a neck or flange 135 which supports the right end of the sleeve 124. The left end of the shell assembly is closed by an assembly of washers 136 and 138 which are riveted together by spinning over at 140 the reduced shank 142 of the core 60 having a conical recess 146 for receiving the companion conical extension 148 of the armature 61 which slides in the sleeve 124 and is prevented from turning therein by providing the sleeve 124 with a lug 150 received by a groove 152 provided in the armature 61. When the starter magnet is energized the armature extension 148 moves into the recess 146 and seats upon the core 60 thereby forming a magnetic seat therewith. The metallic parts of the starter magnet are magnetizable with the exception of the sleeve 124 which is made of brass or other non-magnetizable metal. The sleeve flange 130 being received between one of the end plates 136 and one of the washers 128, and the rib 129 being received between the end washer 132 and the other washer 128, prevents any longitudinal shifting of the spool and windings.

Suitably secured by screws or in any other desirable way at the end of the magnet opposite to that in which the armature slides is a housing 154 which encloses the fixed contacts 40 and 42 of the starting motor switch, these contacts being carried by a suitable bracket 156 secured by screws 156a to the end washer 138 and received within the housing 154.

The core 60 has an axial bore 158 in which the metal plunger 64 is adapted to slide and which normally occupies the position shown in Figure 2 with one of its ends projecting into the depression 146 so that it is adapted to be engaged by the armature 61 as the latter moves to the left

upon energization of the magnet. The opposite end of the plunger 64 is bored at 161 and receives the pin 162 which is riveted in the bracket 156 and upon which the plunger 64 slides when engaged by the armature 61. The spring 174 which normally holds the switch open is received between the bracket 156 and a suitable cup-shaped C-washer 166, which is received by a groove 167 of the plunger 64. Against the washer 166 normally rests a flanged collar 168 which is slidable upon the plunger 64 and has mounted thereon, between the flanges thereof, the movable contact member 41 of copper or other suitable metal. The contact member 41 has a central hole through which the collar 168 extends and which is larger than the collar and is separated therefrom by insulating washers 170, while between the contact member 41 and the flanges of said collar 168 are insulating washers 172. A spring 174 surrounds the plunger 64 and is located between a cupped washer 176 (not a C-washer) and a plain washer 178 held by the spring 174 against a C-washer 179 which is received by a groove 180 of the plunger 64. The spring 174 and the washers 178 and 179 are received by a recess 181 provided by the core 60, as shown in Figure 2. The spring 174, therefore, exerts a pressure urging the contact assembly carried by collar 168 against the washer 166.

The contacts 40 and 42 are formed on the ends of binding posts 184 and 182 respectively, to which the wires 34 and 43 are respectively connected, suitable insulating washers being provided to insulate the contacts from the supporting bracket and suitable means being provided to connect the wires referred to, to the binding post. In case the starter control relay 80 is not directly associated with the starter magnet unit as shown in Figure 2, the bracket 156 was provided with a binding post 186 to which the wires 90 and 87 may be attached. In other words, the binding post 186 is the equivalent of the bracket 86 of the diagram to which the wires 87 and 90 are shown to be connected.

A bolt 190 which is screwed into the armature 61 and which carries the pin 74 connecting with the link 75 secures to the armature 61, a washer 191 which is adapted to be engaged by the enlarged head of the bolt 190 so that a leather shield 192 may be clamped between the washer and the armature. This shield is adapted to be fitted around the neck 135 and clamped in position by a split clamp 193 which surrounds said neck and lies outside the leather shield. The purpose of this shield is to prevent dirt and moisture from reaching the armature.

The magnet frame 120 is secured to a bracket 195 by which the starter magnet assembly may be mounted upon the frame of the starting motor in order that the magnet armature 61 may be properly associated with the pinion shifting lever 54.

The magnet upon energization effects three functions seriatim. As the armature moves to the left when the magnet is energized during the first part of its movement and before it engages the plunger 64, it shifts the starter pinion 49 into engagement with the fly-wheel gear 50, then during its continued movement and before it engages the core 60, the plunger 64 is moved to first move the contact 41 into engagement with the contacts 40 and 42 and second, to compress the spring 174 so as to exert a heavy pressure on the contact 41 to insure that proper contact is made

at the starter switch during the engine cranking operation.

Figures 5 to 9 inclusive are views of a control unit comprising an electromagnet and motor switch, described in the foregoing paragraphs, combined with the starter switch relay in a unitary structure. In this form of invention the contacts 40 and 42 of the motor switch are provided by the heads of bolts 184a and 182a respectively, which are longer than the bolts 184 and 182, shown in Figure 4.

Bolts 182a and 184a are insulating supported by a bracket 156b which is a modification of bracket 156, shown in Figure 2. Means for insulating the bolts 182a and 184a from the bracket 156b, comprises insulating plates 200 and 201, between which the bracket 156b is located, and insulating washers 202 and 203, located in the plane of bracket 156b, as shown in Figure 8. Between the head 42 of bolt 182a and the non-conducting plate 201, and surrounding the bolt 182a, is a washer 90b serving as means for connecting the wire 90a, shown more clearly in Figure 6, to the contact or bolt head 42. In order to space the head 40 of bolt 184a the same distance from the non-conducting plate 201, a washer 205 is provided. The bracket 81 which supports part of the starter switch relay 80, as shown in Figure 1, is provided, as shown in Figure 7, with a hole 210 to provide clearance for certain parts of the bracket 156b, and with holes 211 and 212 through which the bolts 182a and 184a extend. Both holes 211 and 212 are substantially larger than the shanks of bolts 182a and 184a. The bolt 182a is insulated from the bracket 81 by the insulating plate 200, insulating washer 213 located in the plane of the bracket 81, and by insulating plate 214. The bolt 184a is electrically connected with the bracket 81 by metal sleeve 220 having a part 221 which extends into the plane of the bracket 81. The washer 213 surrounding the bolt 182a is of such size as to fit snugly within the hole 211 of bracket 81. The shoulder portion 221 in metal sleeve 220 is of such size as to fit snugly within the hole 212 of bracket 81. Thus the bracket 81 is supported upon the bolts 182a and 184a. A non-conducting washer 222, a metal washer 223 and a lock washer 224 surround the bolt 182a. A nut 225 cooperates with the screw threaded portion of bolt 182a. The tightening of this nut on the bolt 182a clamps between the nut and the head 42 of the bolt, the washer 204, plate 201, bracket 156b, plate 200, bracket 81, plate 214, and washers 222, 223 and 224. In order that the bolt 182a will not turn while tightening the nut 225, its shank is provided with a square portion 226 fitting within a corresponding square hole in the plate 201. Thus the bolt 182a is insulating supported by the bracket 156b and insulating supports the bracket 81. A second nut 227 and lock washer 228 are used to attach to the bolt 182a to wire 43, shown diagrammatically in Figure 1.

A non-conducting washer 230 surrounds the metal sleeve 220; a plain washer 231 and a lock washer 232 surround the bolt 184a. A nut 233 cooperates with the threaded part of bolt 184a. The tightening of nut 233 on the bolt 184a clamps between the said nut and head 40 of bolt 184a the metal washer 205, non-conducting plate 201, bracket 156b, non-conducting plate 200, the bracket 81, non-conducting plate 214, metal sleeve 220, non-conducting washer 230, plain washer 231 and the lock washer 232. Thus, the bolt 184a is insulating supported by the bracket

156b and supports the bracket 81 and is electrically connected therewith. In order that the bolt 184a will not turn when tightening the nut 233, the bolt is provided with a square portion 236 fitting within a corresponding square hole in the 5 plate 201. Bolt 184a is provided with a lock washer 237 and a nut 238 by which the wire 34, shown in Figure 1, is secured to the bolt 184a.

Referring to Figures 5, 7 and 9, the bracket 86, shown diagrammatically in Figure 1, is secured to the bracket 81 by rivets 240, and is insulated from bracket 81 by means including an insulating plate 241. These rivets 240 also secure to the bracket 81 terminal plates 242 and 243 to which the end leads of coil 99 are respectively connected. These plates 242 and 243 carry screws 244 and 245 respectively by which the wires 98 and 101 are respectively connected to the plates 242 and 243. Plates 242 and 243 are, of course, insulated from each other and from bracket 81 by non-conducting plates 246, 247 and 248. As shown in Figure 1, the bracket 86 is connected to wires 98 and 101. Referring to Figures 5 and 6, the wires 98 and 101 are fastened to a common terminal clip 250, which clip is secured by screw 251 to bracket 86, said screw passing through a threaded hole 252 in said bracket.

When describing Figure 1 it was stated that the armature 83 is supported by a leaf spring hinge 82 which tends to move the armature 83 against a stop 83a and to separate contact 84 from contact 85. As shown in Figures 5, 7 and 9, the spring 82 is assisted by a spring 260 fixed at one end to the armature 83 and having its free end bearing against a stop 261 provided by a 30 plate 262, which is held in place by the core 100 of the relay and which is provided with an ear 263 which is equivalent to said stop 83a, shown diagrammatically in Figure 1.

While the embodiment of the present invention as herein disclosed, constitutes a preferred form, it is to be understood that other forms might be adopted, all coming within the scope of the claims which follow.

What is claimed is as follows:

1. An electromagnetic device comprising, in combination, a frame, an electromagnet carried by the frame, an armature cooperating with the electromagnet, a movable switch contact supported by the frame and actuated by the armature, a bracket supported by the frame, a stationary switch contact supported by the bracket and engageable by the movable contact, a second bracket supported by the first bracket and electrically connected with the stationary contact, and a control switch for the electromagnet carried by the second bracket and electrically connected therewith.

2. An electromagnetic device comprising, in combination, a frame, an electromagnet carried by the frame, an armature cooperating with the electromagnet, a movable switch contact supported by the frame and actuated by the armature, a bracket supported by the frame, terminal bolts carried by the bracket and providing stationary contacts engageable by the movable contact, a second bracket supported upon said terminal bolts and electrically connected with one of said bolts, and a control switch for the electromagnet carried by the second bracket and electrically connected therewith.

3. An electromagnetic device comprising, in combination, a frame, an electromagnet carried by the frame, an armature cooperating with the electromagnet, a movable switch contact sup-

ported by the frame and actuated by the armature, a bracket supported by the frame and providing a support for the movable contact, a spring supported by the bracket and urging the movable contact away from the bracket, a stationary switch contact supported by the bracket and engageable by the movable contact, a second bracket supported by the first bracket and electrically connected with the stationary contact and a control switch for the electromagnet carried by the second bracket and having one contact electrically connected therewith and another contact electrically connected with a winding of the electromagnet.

4. An electromagnetic device comprising, in combination, a frame, an electromagnet carried by the frame, an armature cooperating with the electromagnet, a movable switch contact supported by the frame and actuated by the armature, a bracket supported by the frame, terminal bolts carried by the bracket and providing stationary contacts engageable by the movable contact, a second bracket supported upon said terminal bolts and electrically connected with one of said bolts, means electrically connecting the other bolt with a winding of the electromagnet and a control switch for the electromagnet carried by the second bracket and having one contact electrically connected therewith and another contact electrically connected with a winding of the electromagnet.

5. In an electromagnetically controlled engine starting apparatus having, in combination, an electrical motor provided with a field frame, an armature rotatable therein and adapted when rotated to operate the engine, a means for controlling the operation of the motor comprising a magnet housing mounted on top of the motor frame, windings within the housing, a magnet armature slidably supported by the magnet housing, a switch for controlling the operation of the motor and also supported by said magnet housing and means for connecting the magnet armature with said switch to operate the latter.

6. In an electromagnetically controlled engine starting apparatus having, in combination, an electric motor provided with a field frame, an armature rotatable therein and adapted when rotated to operate the engine, a means for controlling the operation of the motor comprising a magnet housing mounted on top of the motor frame, windings within the housing, a magnet armature slidably supported by the magnet housing, a switch for controlling the operation of the motor and also supported by said magnet housing, means for connecting the magnet armature with said switch to operate the latter, and means for causing the magnet armature to operate the switch only after a substantial portion of the movement of the magnet armature has taken place.

7. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings within the housing, a magnet armature slidably supported by the magnet housing and movable in a path substantially parallel to the axis of the motor shaft, a switch for controlling the operation of the motor also supported by the magnet housing, and means

whereby said switch is operated by the magnet armature.

8. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings within the housing, a magnet armature slidably supported by the magnet housing and movable in a path substantially parallel to the axis of the motor shaft, a switch for controlling the operation of the motor also supported by the magnet housing, and means for operating said switch extending into the path of movement of said armature whereby said switch operating means is engaged by the armature during its movement.

9. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings within the housing, a magnet armature slidably supported by the magnet housing and reciprocable in a path substantially parallel to the axis of the motor shaft, a switch for controlling the operation of the motor also supported by the magnet housing and means for operating said switch comprising a member extending into the path of movement of said armature and engageable by said armature as it moves in one direction to close the switch.

10. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings within the housing, a magnet armature slidably supported by the magnet housing and reciprocable in a path substantially parallel to the axis of the motor shaft, a switch for controlling the operation of the motor supported by the end of said housing and toward which the armature moves as the magnet is energized and a member for operating said switch and adapted to be energized by said armature and moved to close the switch when said armature is moved upon energization of the magnet.

11. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings within the housing, a magnet armature slidably supported by the magnet housing and reciprocable in a path substantially parallel to the axis of the motor shaft, a bracket supported at one end of the magnet housing, a switch for controlling operation of the motor having fixed contacts supported by said bracket and a movable contact supported by said bracket and the magnet housing and adapted to be moved into engagement with a fixed contact to close the motor circuit by said reciprocable armature.

12. In an electrically controlled engine starter

apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings and an armature within the housing, a bracket supported by the magnet housing, a switch for controlling operation of the motor having fixed contacts supported by said bracket, a movable contact adapted to cooperate with said fixed contacts and means for moving said movable contact into engagement with said fixed contacts to close the motor circuit upon energization of said magnet.

13. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame windings within the housing, a magnet armature slidably supported by the magnet housing and reciprocable in a path substantially parallel to the axis of the motor shaft, a bracket supported at one end of the magnet housing, a switch for controlling operation of the motor having fixed contacts supported by said bracket and a movable contact carried by a supporting member supported by the bracket and magnet housing and movable relatively thereto, said member being moved by the magnet armature when the magnet is energized to close said switch.

14. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings and an armature within the housing, a bracket supported by the magnet housing, a switch for controlling operation of the motor comprising fixed and movable contacts supported by said bracket, and a second switch also supported by said bracket for controlling operation of the magnet.

15. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings and an armature within the housing, a bracket supported by the magnet housing, a switch for controlling operation of the motor comprising fixed and movable contacts supported by said bracket, a second switch also supported by said bracket for controlling the operation of the magnet and a second magnet supported by said bracket for controlling the operation of said second switch.

16. In an electrically controlled engine starter apparatus having, in combination, an electric motor provided with a field frame and a shaft rotatable therein which, when rotated, is operable to rotate the engine shaft, a means for controlling the operation of said motor comprising a magnet having a housing mounted on top of the motor frame, windings and an armature within the housing, a bracket supported by the magnet housing, a switch for controlling operation of

the motor comprising fixed and movable contacts supported by said bracket and operable by said armature when the magnet is energized, a second switch also supported by said bracket for controlling the operation of said magnet and a second magnet also supported by said bracket for controlling the operation of said second switch.

17. In an electrically controlled engine starting apparatus having, in combination, an electric motor provided with a field frame and a rotatable motor shaft adapted when rotated to operate the engine, a means for controlling the operation of said motor comprising a magnet having a housing mounted on top of the motor frame, a winding assembly within the housing comprising a tubular sleeve of nonmagnetizable metal and windings surrounding the sleeve, a core, cover plates at the ends of said housing for supporting the sleeve and core, an armature slideable within the sleeve and movable toward the core, a switch supported on one of the cover plates and controlling the operation of said motor, and a switch operating rod extending through the core to a position to be engaged by said armature and moved thereby to a position to close said switch upon energization of said magnet.

18. In an electrically controlled engine starting apparatus having, in combination, an electric motor provided with a field frame and a rotatable motor shaft adapted when rotated to operate the engine, a means for controlling the operation of said motor comprising a magnet having a housing mounted on top of the motor frame, a winding assembly within the housing comprising a tubular sleeve of nonmagnetizable metal and windings surrounding the sleeve, a core, cover plates at the ends of said housing for supporting the sleeve and core, an armature slideable within the sleeve and movable toward the core, a switch for controlling operation of said motor and having stationary contacts carried by a bracket supported on one of said cover plates, a switch operating rod supporting a movable contact and extending through the core into a position to be engaged by said armature and moved to a position to engage the movable contact with said fixed contacts upon energization of said magnet.

19. In an electromagnetically controlled engine starting apparatus having, in combination,

an electric motor provided with a field frame, an armature rotatable therein and adapted when rotated to operate the engine, a means for controlling the operation of the motor comprising a magnet housing mounted on top of the motor frame, windings within the housing, a magnet armature slidably supported by the magnet housing, means for preventing any rotary movement of the armature as it slides within the magnet housing, a switch for controlling the operation of the motor and also supported by said magnet housing and means for connecting the magnet armature with said switch to operate the latter.

20. In an electromagnetically controlled engine starting apparatus having, in combination, an electric motor provided with a field frame, an armature rotatable therein and adapted when rotated to operate the engine, a means for controlling the operation of the motor comprising a magnet housing mounted on top of the motor frame, windings within the housing, a magnet armature slidably supported by the magnet housing, a sleeve within which the armature slides provided with a key on its inner surface, said armature having a slot formed in its outer surface for cooperation with said key to prevent any rotary movement of the armature, a switch for controlling the operation of the motor and also supported by said magnet housing and means for connecting the magnet armature with said switch to operate the latter.

21. In an electromagnetically controlled engine starting apparatus having, in combination, an electric motor provided with a field frame, an armature rotatable therein and adapted when rotated to operate the engine, a means for controlling the operation of the motor comprising a magnet housing mounted on top of the motor frame, windings within the housing, a magnet armature slidably supported by the magnet housing and having a slot formed in its outer surface, a thin metal sleeve within which the armature slides, said sleeve being bent inwardly at a point on its periphery to form a key for cooperation with said slot to prevent any rotary movement of the armature, a switch for controlling the operation of the motor and also supported by said magnet housing and means for connecting the magnet armature with said switch to operate the latter.

JOHN B. DYER.
